2,082,801

PRODUCTION OF HIGH OCTANE GASOLINE

Filed Sept. 16, 1933

UNITED STATES PATENT OFFICE

2,082,801

PRODUCTION OF HIGH OCTANE GASOLINE

Eugene J. Houdry, Woodbury, N. J., assignor to
Houdry Process Corporation, Dover, Del., a cor-
poration of Delaware

Application September 16, 1933, Serial No. 689,695

5 Claims. (Cl. 196—52)

This invention relates to the production of desirable marketable hydrocarbon products, such as benzine, gasoline, naphtha, kerosene, and the like. More particularly it has to do with the production of motor fuel of high quality and high anti-knock rating, especially in a once through operation, from crude starting material, wherein the only other liquid product is a clean residual oil in the boiling range of gas oil and suitable for use as Diesel oil, domestic fuel oil, or as charging stock for further conversion. In certain respects the invention may be considered as a further development of or improvement upon my copending applications, Serial Nos. 674,129 and 687,553 filed on June 3, 1933, and August 31, 1933, respectively.

One object is to effect an improved once through operation from crude starting material without internal recycling and without separation of intermediate products so as to produce directly, only the two low and high boiling liquids referred to above and lean gas. Another object is to simplify the regulation of pressure conditions throughout the system. Another object is to provide for flexibility of control so that a maximum yield of desirable high and low boiling products may be secured from any crude starting material. Other objects will be apparent from the detailed description which follows.

The invention contemplates a once through system made up of two pressure zones. In the first zone all of the transforming reactions take place by which conversion into light products is effected. The second zone takes care of the refining and stabilizing of the light products. Each zone can be operated independently of the other, but they are preferably joined together to form a complete system for the conversion of crude starting material. All transforming, refining and polymerizing operations are effected with or upon contact masses capable of performing the desired reactions and preferably arranged in pairs or multiples thereof to provide for regeneration in place so that the process may be continuous with each reaction case alternately on stream and in regeneration. In the first or transforming zone, provision is made for reforming the heavy naphtha and straight run gasoline from the crude topping still so as to improve the octane rating of these hydrocarbons, for transforming a middle or deep cut, and for vaporizing and transforming the bottoms. The products from all these transforming operations discharge into the same fractionating tower, which throws down the clean residual oil product and passes

the lighter hydrocarbons. Since the transforming operations in the first zone take place at low pressure, the charging pump for the crude material supplies the pressure for this entire zone.

The second zone is established immediately after the said fractionating tower, and a suitable vapor pump is provided capable of imposing the required pressure in the outlet line. The second zone provides for absorption of the gasoline from the rich gases, the refining of condensed light hydrocarbons along with the wild gasoline vapors from the absorption step, and the stabilizing of the light products after cutting the same to the desired end point. The high quality completely refined and stabilized motor fuel or gasoline is the final product of the second zone. The other liquid product, clean residual or Diesel oil, is recovered in liquid form from the bottom of the fractionating tower at the end of the first zone with some additions from the end point fractionator of the second zone.

The single view in the accompanying drawing indicates in a diagrammatic manner the operation of the process of the present invention and a preferred arrangement of apparatus for practising the same.

The crude oil or other suitable starting material passes by line 1 to pump 3 which forces the same through a vaporizing or topping still 4 which discharges its vapors into a large fractionating tower 5 controlled by a cooling coil 5a. Pump 3 is utilized to impose pressure adequate to pass the starting material entirely through the first or transforming zone, where the transforming operations take place at pressures normally from atmospheric up to 20 pounds per square inch. Usually a pressure of thirty pounds per square inch in fractionator 5 is enough, but, under special circumstances, it may be increased, as to sixty pounds, to take care of the back pressures in the heating coils which follow. A number of cuts are taken from fractionator 5, such as an overhead cut through valved line 6, or valved line 6a to storage, a heavy naphtha cut through valved line 7, a middle or deep cut in the gas oil boiling range through line 8, and a residuum or bottom cut through valved outlet 9. Each fraction is arranged to be transformed, preferably by catalytic action at low or atmospheric pressure, so as to produce desirable motor fuels in both the low and high boiling ranges, especially a gasoline of high octane rating.

The heavy naphtha cut in line 7, with or without the overhead vapor cut in line 6, is conducted through heater 10, where its temperature is

raised to the range of 800° to 950° F. and passed by line 11 and suitable valved connections into a series of catalytic reforming chambers 12, arranged in pairs or multiples thereof for alternate 5 operation on stream and in regeneration. These chambers contain suitable catalytic material for reforming the light hydrocarbon vapors to improve their octane rating, which may consist of inert, porous material, such as china clay or pumice stone, or of activated hydrosilicate of alumina, preferably in molded form and containing oxides of one or more of the following metals: vanadium, chromium, tungsten, and molybdenum. The reformed vapors leave cases 12 by 10 15 valved connections to line 13.

The middle or deep cut is conducted by line 8 through heater coil 14, where the temperature is raised to the range of 750° to 950° F., and thence by line 15 having valved connections to a series 20 of catalytic transformers 16 arranged in pairs or multiples thereof for alternate operation on stream and in regeneration. These cases contain suitable catalytic adsorptive material capable of effecting the desired transformation, such as 25 molded pieces of activated hydrosilicate of alumina. The products of the transformation leave cases 16 through suitable valved connections to a line 17.

The bottoms from tower 5 are conducted by 30 line 9, together with superheated steam in suitable amount admitted by valved branch line 18, into a series of contact vaporizers 19 arranged in pairs or multiples thereof for alternate operation on stream and in regeneration. These vaporizers 35 may be of the type disclosed in United States Patent No. 1,806,997, issued to Alfred Joseph on May 26, 1931, but are preferably of the improved type and arrangement disclosed in my copending application, Serial No. 670,954, filed May 13, 1933 40 which issued February 5, 1935, as Patent No. 1,989,927. These chambers contain suitable inert, porous contact masses, such as broken fragments of brick, pieces of pumice, molded units of china clay, or preferably the inert carrier material 45 disclosed in United States Patent No. 1,818,403, issued to Alfred Joseph on August 11, 1931. The vaporized products leave chambers 19 through suitable valved connections to line 20, which conducts them through valved connections into a 50 series of catalytic transforming chambers 21 arranged in pairs or multiples thereof for alternate operation on stream and in regeneration, and conforming in all respects to catalytic chambers 16 and containing the same contact material. 55 The transformed vapors leave by suitable valved connections to line 21a and thence by line 22 which joins with lines 17 and 13 so that all the transformed vapors are discharged by connection 22 into fractionating tower 23, which may 60 be controlled by a cooling coil 23a. Tower 23 makes a separation of the high boiling hydrocarbons in the form of clean residual oil suitable for use as Diesel fuel, which leaves the bottom of fractionator 23 by a valved line 24, and is conducted to storage. The low boiling hydrocarbon vapors and gases leave fractionator 23 by an 65 overhead line 25 and pass beyond the first zone, the division between the two zones being indicated by the broken line a.

70 Overhead line 25 leads to a pump 26, which marks the beginning of the second zone and imposes a pressure not exceeding 100 pounds per square inch, and normally about 60 pounds per 75 square inch. The vapors now under pressure pass through a condenser 27 and thence into a

separator 28, the condensate leaving by valved line 29, while the rich gases pass by line 30 into an absorber 31 of any suitable or desired type. The absorber shown utilizes liquid absorbent, which leaves the bottom of unit 31 in a rich condition, and is conducted by line 32 into still 33, where the wild gasoline vapors are driven off and leave by valved line 34. The lean absorbent liquid is forced from the bottom of still 33 through line 35 by a suitable pump or circulator (not shown), through a cooler 36, and thence into the top of absorber 31. The lean gases leave the top of the absorber by valved line 37.

The light hydrocarbon condensate in line 29, and the wild gasoline vapors in line 34, are conducted together by a line 38 through a heater coil 39, where the temperature is raised to the range of 500° to 700° F., and discharged into line 40 having valved connections to a series of catalytic refining cases 41 arranged in pairs or multiples thereof for alternate operation on stream and in regeneration. These chambers contain suitable adsorptive catalytic material adapted to purify and refine the light hydrocarbons and to polymerize the unsaturated components separated from the fixed gases, preferably comprising molded pieces of activated hydrosilicate of alumina containing small amounts of metallic oxides, such as those of copper, nickel, and cobalt. The refined vapors leave chambers 41 by suitable valved connections to a line 42 which discharges into fractionating tower 43 provided to fix the end point of the light hydrocarbon motor fuel. Any polymers separated out in fractionator 43 are in the form of a clean oil of the Diesel type, and are withdrawn from the bottom of the fractionator by a valved line 44 which joins line 24 and conducts the polymers to storage along with the Diesel type motor fuel from fractionator 23.

The overhead vapors passing control coil 43a are conducted by a line 45 through condenser 46 into a separator 47, whence water is withdrawn through a valved line 48. The hydrocarbon liquids, vapors, and gases are withdrawn from the upper part of separator 47 by a line 49 which leads to a heater coil 50, whence the hydrocarbons are conducted by line 51 into a stabilizer 52. The lean gases escape from the top of the stabilizer through a valved line 53, while the refined and stabilized light end point hydrocarbons or gasoline are withdrawn by valved line 54 and conducted through a cooler 55 and thence to storage.

As indicated above, the catalytic reforming chambers 12, the catalytic transforming chambers 16 and 21, the contact vaporizing chambers 19, and the catalytic refining chambers 41 are provided in pairs or multiples thereof, to permit continuous operation of the system, and are arranged for regeneration in place by known means. The regeneration is preferably effected by oxidation, so that all tarry and coky or sulphurous deposits left in any of the contact masses may be entirely eliminated during the regenerating periods. The regenerating medium may be air, diluted as required by flue gas or steam, but all indications of regenerating apparatus are omitted in order to simplify the drawing.

Since the catalytic transforming chambers 21 following the contact vaporizers 19 are the same as catalytic transformers 16 and contain the same catalytic material, transforming cases 21 may be omitted and the vapors conducted by line 20 directly into line 15, as indicated in my aforesaid copending application Serial No. 687,553. Such a simplified arrangement may be highly desirable.

and economical in small installations, but in large installations, there is a sufficient quantity of the bottoms to be withdrawn by line 9 and sufficient differences over the side stream withdrawn through line 8 to warrant or to require somewhat different pressure and temperature conditions in the transforming cases 21, as compared with transforming cases 16, if a maximum transformation into light products of high quality is to be obtained from both fractions. Since the drawing is diagrammatic in character, other apparatus, including heat exchangers, coolers, etc. not essential to the understanding of the invention, are also omitted.

15 If desired, the application of pressure in the second zone may be deferred until after the separator 28 by the use of a liquid pump in line 29 and of a gas pump in line 30. Such an arrangement is within the spirit of the invention, 20 but involves the use of two pumps instead of one, as in the form shown, and has the additional disadvantage that condensing of the overhead from fractionator 28 is not effected under pressure.

From the above it will be apparent that the 25 present invention permits the grouping of all cracking and treating apparatus around a skimming or topping unit without requiring any tanks for the storage of intermediate products. This means compactness of plant, simplicity of equipment, smaller investment and operating costs, 30 and a reduced staff of operators. By arranging the apparatus in definite pressure zones, pumping equipment is much reduced without any sacrifice of efficiency or of flexibility of operation.

35 I claim as my invention:

1. Process for the production of high quality motor fuel in a once through operation from crude hydrocarbon starting material which comprises vaporizing the starting material, fractionally condensing the vapors into a plurality of cuts, heating and transforming the cuts individually but simultaneously by contacting the same at reaction temperature with beds of catalytic material capable of effecting the desired transformation and of producing clean products, combining the products of the transforming reactions, fractionating the combined products to separate out and withdraw as a finished product a liquid fraction in the form of a clean motor fuel oil of the Diesel type, subjecting the overhead vapors from the last fractionating zone to pressure, condensing the compressed vapors and separating the same into condensate and uncondensed material, separating the uncondensed material into light hydrocarbons and lean gas, removing the lean gas, combining the light hydrocarbons and the condensate and passing the same together through a heating and vaporizing zone, subjecting the heated and vaporized material to the action of a bed of catalytic material capable of refining and polymerizing the same, fractionating the refined material to remove liquid polymers outside the gasoline boiling range, and removing entrained gases from the remaining material to produce a second motor fuel in the form of finished end-point gasoline.

2. In the production of high quality motor fuels in a continuous once through operation from crude hydrocarbon starting material, the operating process which comprises imposing a pressure on the starting material, distilling and fractionating the starting material under a pressure of approximately 30 pounds per square inch, separately vaporizing and separately transforming all of the fractions in vapor phase in the

temperature range of 750 to 950° F. by the action of catalytic masses comprising essentially blends of silica and alumina having selective adsorptive properties and capable of producing clean products, combining the products of the transforming operations and fractionating the same to separate out a single liquid or bottom fraction which is clean finished motor fuel oil of the Diesel type, continuously passing the overhead fraction from the last fractionating step into a second zone under an increased pressure of the order of 60 pounds per square inch, condensing the compressed vapors to produce condensate and light hydrocarbons and gases, separating the said light hydrocarbons from the gases, combining the said light hydrocarbons with the condensate and subjecting them to a heating and vaporizing step, catalytically refining the resulting material in vapor phase in the temperature range of 500 to 700° F. by the action of a catalytic mass comprising essentially a blend of silica and alumina with other metallic compounds having selective adsorptive properties, fractionating the refined material to remove a liquid fraction which is clean and which is added to the Diesel type motor fuel, and stabilizing the overhead products of the last named fractionating step by the removal of entrained gases to obtain a second motor fuel in the form of finished and stabilized end-point gasoline.

3. In the production of high quality motor fuels in a continuous once through operation from crude hydrocarbon starting material, the operating process which comprises heating and at least partly vaporizing the starting material under pressure in a primary transforming zone, fractionating the heated and vaporized material into an overhead cut, a heavy naphtha cut, a gas oil cut and a bottom cut, reforming the heavy naphtha cut with or without the overhead cut in vapor phase by the action of an adsorptive contact mass containing metallic oxides from the group containing vanadium, chromium, tungsten and molybdenum, revaporizing and transforming the gas oil cut at transforming temperature by the action of an adsorptive contact mass comprising activated hydrosilicate of alumina, revaporizing the bottom cut with steam in the presence of inert absorptive material and then transforming the vapors in the temperature range of 750 to 950° F. by the action of an adsorptive contact mass comprising activated hydrosilicate of alumina, effecting the aforesaid operations separately but simultaneously and at pressures derived from said heating and fractionating steps, fractionating together all the products of all the aforesaid operations to separate out as a finished product a single liquid fraction which is a clean motor fuel oil of the Diesel type, continuously passing the overhead fraction from the last fractionating step into a second zone and subjecting it to a higher pressure than in said primary transforming zone which pressure continues substantially throughout the rest of the process, subjecting the last named overhead fraction to condensation to produce condensate and uncondensed lighter material, removing from said lighter material by an absorption operation the lean gas to leave certain desirable light hydrocarbons, combining said desirable light hydrocarbons with the aforesaid condensate and subjecting them together to a heating and vaporizing operation, subjecting the vaporized and heated material in the temperature range of 500° to 700° F. to the action of a

75

refining catalyst comprising essentially activated hydrosilicate of alumina, fractionating the products to remove a heavier liquid fraction which is added to the aforesaid Diesel type motor fuel and to secure a desired end-point overhead material, and subjecting the last named overhead material to a stabilizing operation involving the removal of entrained light gases thereby to produce a second motor fuel in the form of finished stable end-point gasoline of desirable antiknock quality.

4. Apparatus for the production of high quality motor fuel in a once through operation from crude hydrocarbon starting material comprising a vaporizing or topping still into which the crude starting material is fed, a fractionator for the vapors from said still, means withdrawing material from said fractionator in a plurality of cuts, a plurality of heating means and catalytic cases for transforming each of said cuts individually but simultaneously, a single fractionator into which all of the transformed material from said cases is discharged, an outlet from the lower part of said last named fractionator for withdrawing as a finished product a liquid fraction in the form of a clean motor fuel oil of the Diesel type, an outlet line from the upper part of said last named fractionator for the overhead material, a pump in said line for imposing on said vapors a pressure sufficient to force the latter through the remainder of the apparatus, condensing and separating means into which said vapors are forced by said pump, means for separating the uncondensed material into light hydrocarbons and lean gas, a heater for vaporizing the condensate receiving the latter and said light hydrocarbons, refining cases containing catalytic masses receiving the vaporized condensate and heated light hydrocarbon mixture, a fractionator receiving the products of said cases, and means for removing entrained gases from the overhead fraction from said fractionator to produce a second motor fuel in the form of finished end point gasoline.

5. Apparatus for the production of high quality motor fuel in a once through operation from crude hydrocarbon starting material arranged in two pressure zones, the first zone comprising a feed line having a liquid pump therein, a topping still into which said line and said pump discharge, a fractionator connected to the outlet of said topping still, lines extending from various levels of said fractionator for withdrawing therefrom a plurality of cuts, a heater and at least one catalytic transformer in each of said last named lines, a second fractionator connected to all of said catalytic transformers to receive the transformed material therefrom and for separating it into a single liquid fraction which is a high boiling motor fuel of the Diesel type and into an overhead fraction, a line extending from the upper part of said second fractionator for removing said overhead fraction, a vapor pump in said last named line marking the beginning of the second pressure zone, said second zone thereafter comprising a condenser into which said last named line and vapor pump discharge, a separator for condensate and uncondensed material connected to said condenser, absorbing means receiving said uncondensed material from said separator and separating out light hydrocarbons from the fixed gases, a heater, means conducting the condensate from said separator and the light hydrocarbons from said absorbing means to said heater, a catalytic refining case connected to said heater to receive the heated and vaporized condensate and light hydrocarbons, an end point fractionator connected to said case to receive the refined products thereof, a discharge line from the upper end of said end point fractionator, and a stabilizing means in said last named line for the overhead vapors for removing entrained fixed gases therefrom so as to produce a second motor fuel in the form of finished end point gasoline.

refining catalyst comprising essentially activated hydrosilicate of alumina, fractionating the products to remove a heavier liquid fraction which is added to the aforesaid Diesel type motor fuel and to secure a desired end-point overhead material, and subjecting the last named overhead material to a stabilizing operation involving the removal of entrained light gases thereby to produce a second motor fuel in the form of finished stable end-point gasoline of desirable antiknock quality.

4. Apparatus for the production of high quality motor fuel in a once through operation from crude hydrocarbon starting material comprising a vaporizing or topping still into which the crude starting material is fed, a fractionator for the vapors from said still, means withdrawing material from said fractionator in a plurality of cuts, a plurality of heating means and catalytic cases for transforming each of said cuts individually but simultaneously, a single fractionator into which all of the transformed material from said cases is discharged, an outlet from the lower part of said last named fractionator for withdrawing as a finished product a liquid fraction in the form of a clean motor fuel oil of the Diesel type, an outlet line from the upper part of said last named fractionator for the overhead material, a pump in said line for imposing on said vapors a pressure sufficient to force the latter through the remainder of the apparatus, condensing and separating means into which said vapors are forced by said pump, means for separating the uncondensed material into light hydrocarbons and lean gas, a heater for vaporizing the condensate receiving the latter and said light hydrocarbons, refining cases containing catalytic masses receiving the vaporized condensate and heated light hydrocarbon mixture, a fractionator receiving the products of said cases, and means for removing entrained gases from the overhead fraction from said fractionator to produce a second motor fuel in the form of finished end point gasoline.

5. Apparatus for the production of high quality motor fuel in a once through operation from crude hydrocarbon starting material arranged in two pressure zones, the first zone comprising a feed line having a liquid pump therein, a topping still into which said line and said pump discharge, a fractionator connected to the outlet of said topping still, lines extending from various levels of said fractionator for withdrawing therefrom a plurality of cuts, a heater and at least one catalytic transformer in each of said last named lines, a second fractionator connected to all of said catalytic transformers to receive the transformed material therefrom and for separating it into a single liquid fraction which is a high boiling motor fuel of the Diesel type and into an overhead fraction, a line extending from the upper part of said second fractionator for removing said overhead fraction, a vapor pump in said last named line marking the beginning of the second pressure zone, said second zone thereafter comprising a condenser into which said last named line and vapor pump discharge, a separator for condensate and uncondensed material connected to said condenser, absorbing means receiving said uncondensed material from said separator and separating out light hydrocarbons from the fixed gases, a heater, means conducting the condensate from said separator and the light hydrocarbons from said absorbing means to said heater, a catalytic refining case connected to said heater to receive the heated and vaporized condensate and light hydrocarbons, an end point fractionator connected to said case to receive the refined products thereof, a discharge line from the upper end of said end point fractionator, and a stabilizing means in said last named line for the overhead vapors for removing entrained fixed gases therefrom so as to produce a second motor fuel in the form of finished end point gasoline.
